UNITED STATES PATENT OFFICE.

PHILIP A. MYERS, OF ASHLAND, OHIO, ASSIGNOR TO F. E. MYERS & BROTHER, OF SAME PLACE.

DESIGN FOR A DOOR-HANGER TRACK.

SPECIFICATION forming part of Design No. 33,255, dated September 25, 1900.

Application filed July 18, 1900. Serial No. 24,080. Term of patent 14 years.

To all whom it may concern:

Be it known that I, PHILIP A. MYERS, a citizen of the United States, residing at Ashland, in the county of Ashland and State of Ohio, have invented and produced a new and original Design for Door-Hanger Tracks, of which the following is a specification, reference being had to the accompanying drawings, forming a part thereof.

Figure 1 is a front elevation of such a track, showing my new design; Fig. 2, an end view of the same, showing that aspect thereof; and Fig 3 a rear elevation thereof.

As shown in the drawings, the leading or material feature of my design consists in parallel lines *a* and *b* and in projections beneath the line *b*, formed by the lines *c* and *d*, such projections being at intervals, as shown in Fig. 1, while the said leading or material feature is further shown in Fig. 2 by the lines *e* and *f*, which join the surfaces defined by the lines *a* *b*, and being still further shown in Fig. 2 by the substantially-parallel lines *g* and *h*, extending laterally from the line *f* and the lines *i* and *j*, which curve into the lines *g* and *h* and are substantially at a right angle

thereto, thus giving the aspect of substantially a parallelogram between the lines *a*, *b*, *e*, and *f*, and an elbow or substantially right-angled figure between the lines *g*, *h*, *i*, and *j*. 30 Circular lines *k* in Fig. 1 define openings in the surfaces constituted of the lines *c* *c* and *d*. At one end of the figure defined by the lines *a* *b* is a depression or receding surface defined by the line *a'*, and at the other end is 35 a projection defined by the line *b'*. In Fig. 2 said depression *a'* is viewed by looking into it. Fig. 3 shows a rear view, being the reverse of Fig. 1.

Having thus fully described my invention, 40 what I claim as new, and desire to secure by Letters Patent, is—

The design for a door-hanger track, herein shown and described.

In testimony whereof I have signed my 45 name to this specification in the presence of two subscribing witnesses.

PHILIP A. MYERS.
